(57) **CLAIM**

The ornamental design for a transparent cap, as shown and described.

DESCRIPTION

FIG. 1 is a top perspective view of a transparent cap according to the invention;

FIG. 2 is a bottom perspective view thereof;

FIG. 3 is a top plan view thereof;

FIG. 4 is a bottom plan view thereof;

FIG. 5 is a side elevational view thereof;

FIG. 6 is a side elevational view thereof, opposite that shown in FIG. 5;

FIG. 7 is a top perspective view thereof, with respect to a bottle; and,

FIG. 8 is a top perspective view thereof, with respect to a bottle.

Elements in the figures shown in even broken lines are for illustrative purposes only and form no part of the claimed invention.
